US00D751500S

(12) **United States Design Patent**
Shimota et al.(10) **Patent No.:** US D751,500 S
(45) **Date of Patent:** ** Mar. 15, 2016(54) **BATTERY CARTRIDGE**

- (71) Applicant: **Wilson Tool International Inc.**, White Bear Lake, MN (US)
- (72) Inventors: **Jon M. Shimota**, Stillwater, MN (US); **John H. Morehead**, New Richmond, WI (US)
- (73) Assignee: **Wilson Tool International Inc.**, White Bear Lake, MN (US)

(***) Term: **14 Years**(21) Appl. No.: **29/498,321**(22) Filed: **Aug. 1, 2014**(51) LOC (10) Cl. **13-02**

Primary Examiner — Rosemary K Tarcza*Assistant Examiner* — Sanjeev Paul(74) *Attorney, Agent, or Firm* — Fredrikson & Byron, P.A.**CLAIM**

We claim the ornamental design for a battery cartridge, as shown and described.

DESCRIPTION

FIG. 1 is a perspective view of my new design for a battery cartridge;

FIG. 2 is front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines, as provided, form no part of the claimed design.

1 Claim, 2 Drawing Sheets(56)
